UNITED STATES PATENT OFFICE.

SAMUEL G. RICHARDS, OF DES MOINES, IOWA.

SIGNAL DEVICE FOR VEHICLES.

Application filed March 29, 1927. Serial No. 179,276.

This invention relates to that class of signal devices especially designed for use on automobiles and to be operated manually for indicating to others whether the operator 5 intends to turn to the right or left or to stop.

My object is to provide a signal device of this character of simple, durable and inexpensive construction, that may be operated 10 conveniently by the operator, and which will accurately position the indicating mark or name in its proper position relative to the illuminated portion, and in which the operator may know by the movement of the 15 operating knob just when the indicator is in its proper position relative to the transparent portion.

My invention consists in the construction, arrangement and combination of the various 20 parts of the device, whereby the objects contemplated are attained, as hereinafter more fully set forth, pointed out in my claim, and illustrated in the accompanying drawings, in which:

25 Figure 1 shows a side elevation of a signal embodying my invention.

Figure 2 shows a horizontal sectional view of same, and shows a top or plan view of same with the casing shown in section.

30 Figure 3 shows a side elevation of same with the casing shown in section; and

Figure 4 shows an enlarged detail view partly in section showing the manually operated device for turning the indicator device.

35 Figure 5 shows a reduced illustration of a signal embodying my invention as viewed from the side opposite from that shown in Figure 1.

40 Referring to the accompanying drawings, I have used the reference numeral 10 to indicate generally the frame of the device. At the outer end of the frame it is preferably formed of circular shape and is completely

45 enclosed. This circular portion of the frame is formed near its top with an opening covered by a glass or other transparent panel 11, through which the signal, hereinafter described, may be seen.

50 In the central portion of the circular part of the frame is a rotatable shaft 12 having thereon a cylindrical pulley body 13, which may be made of wood, hard rubber or the like. Fixed to each side of this pulley body 13 is a disk 15 of transparent material such as mica. At three points in each transparent

disk there is provided a signal mark, the central one preferably having the signal mark "Stop", and the end ones preferably having arrows. These disks are firmly connected with each other by means of a metal brace 16 rigidly uniting them and the disks are also fixed to the ends of the pulley body 13. Fixed to the outer frame are two stops 17. Each is preferably made with a cushion surface of leather or the like 18, and fixed to the cross brace 16 is a cushion member 19 designed to engage with the cushion members 18, and thereby limit the movement of the rotary disks. Supported within the space between the disks is an electric lamp 20 fixed to a bracket 21.

At the opposite end of the casing there is a shaft 22 having a knob 23 at its outer end, and a pulley 24 fixed to its inner end. 75 This shaft is capable of sliding, as well as of rotary movement. A spring 25 is interposed between one end of the pulley 24 and the adjacent wall of the casing to yieldingly hold the shaft with the knob 23 at its outer limit of movement, and formed in the casing or frame are three round openings 26, shown in Figure 4 and by dotted lines in Figure 3, and fixed to the pulley 24 is a round pin 27, designed to enter said openings one at a time.

80 For operating the pulley member 13 from the pulley member 24, I preferably provide a flexible chain or belt 28, which is wound one or more turns upon the pulley 13, and pinned securely to it to prevent slipping, and then passed around the pulley 24, to which it is also securely pinned to prevent slipping. In the central portions of the upper and lower portions of the chain 28 are springs 29, to apply tension to the chains and prevent them from becoming lax through use, or rattling. A switch 30, or the like, is provided for controlling the current to the lamp 20.

85 It is obvious that my improved signal device is of extremely simple and inexpensive construction, and may be made of very simple and inexpensive materials, and quickly and easily assembled. It is easily installed and exceedingly useful as a safety precaution in driving automobiles.

90 In practical use, and assuming that the device is attached to an automobile, the light may be turned on and will show 105 through the glass covered part of the casing or frame. Then the operator grasps the 110

knob 25 and first pushes it forwardly until the pin 27 is free from the opening 26. He then rotates it until the desired signal appears through the illuminated glass covered opening, and until the lock 18 engages the lock 17 when the pin 27 enters the adjacent opening 26, which is so positioned that when these locks contact and the pin does enter, the signal will be held firmly centered in the mica covered opening. After the automobile has either stopped or turned to the right or left, as indicated by the signal, the operator shuts off the lamp and turns the rotary disk to its normal position.

This operation is made very easily because the cushion device 19 will strike one or the other of the cushion devices 18 when the signal device is turned, so that one of the arrows appears through the glass covered opening. The pin 27 is useful when the device is in any of its positions, because it locks the rotating member and prevents it from being accidentally displaced, yet it is readily and easily unlocked when the operator grasps the knob 25, because he first pushes the knob forwardly and thus releases the pin 27. The springs 29 perform a useful purpose in that they keep both of the straight runs of the chain 28 tightly stretched so that the cushion 18 is held, under tension of the spring, firmly against the cushion 17, preventing any misplacement or inaccuracy in the signal, or any rattling of loose parts. These springs also serve as adjusters which will prevent the signal from being tilted either way from its normal position.

I claim as my invention:

In a device of the class described, the com-

bination of a casing having an opening therein through which a signal may be viewed, a signal device within the casing comprising a disk, two signal marks upon the disk, a pulley fixed to the disk, two stop devices fixed to the casing, a stop device fixed to the disk and capable of successively engaging said stop devices fixed to the casing, a second pulley mounted in the casing, a handle for turning it, means for locking it in two positions of its movement, a flexible connecting member passed around the pulleys, and having two portions thereof extended between the pulleys, and a contractile coil spring in each of said portions of the flexible connecting member between the pulleys, said parts being so arranged relative to each other that when the stop device carried by the disk is in engagement with one of the stop devices carried by the casing, one of the signal marks on the disk will be accurately centered relative to the opening in the casing and firmly held in this position by the resiliency of one of the springs, and at the same time the second mentioned pulley will be locked against rotation, and when the stop device carried by the disk is in engagement with the other one of the stop devices carried by the casing, another one of the signal marks will be accurately centered relative to the opening in the casing and the pulley will be locked in position and the other one of said springs will yieldingly hold the disk in its said position, substantially as and for the purposes stated.

Des Moines, Iowa, March 18, 1927.

SAMUEL G. RICHARDS.
